UNITED STATES PATENT OFFICE

2,460,455

ELECTRONIC CIRCUIT

Samuel C. Hurley, Jr., Danville, Ill.; Wilmina L. Hurley, executrix of said Samuel C. Hurley, Jr., deceased, assignor to Wilmina L. Hurley, Danville, Ill.

Application January 4, 1947, Serial No. 720,229

2 Claims. (Cl. 315—179)

1

This invention relates to a means for deionizing a gas-filled tube once it is ionized. It particularly relates to an electronic circuit in which a vacuum tube is connected in series with a gas-filled tube across a source of direct current potential.

One of the problems in this art is the deionization of a gas-filled tube which is connected across a source of direct current potential, once it is ionized. In many operations such as photoelectric inspection operations, registration control operations and others, it is necessary to deionize a gas-filled tube at certain intervals or under certain conditions. It is a characteristic of a gas-filled tube which is connected to a source of direct current potential that once it is ionized, it will continue to ionize until the circuit is broken regardless of how negative in potential the control grid is driven. In the prior art, mechanical switches, time delay relays and other mechanical devices have been used to interrupt the circuit. However, mechanical switches and the like, or anything involving mechanical means for interrupting the circuit, have the disadvantages that are inherent in all mechanical means. Mechanical means are never as instantaneous in their reaction as electronic means. Mechanical means require more upkeep and if a switch sticks, the desired result is not obtained. There is nothing to go wrong with electronic means such as is described herein. Electronic means are instantaneous and will always respond in the required manner.

Broadly my invention comprises connecting the gas-filled tube in series with a vacuum tube across a source of direct current potential. The flow of current through the vacuum tube is accomplished by the control of a control grid in the vacuum tube. The control grid in the vacuum tube will control the flow of current through the circuit and if sufficient negative potential is placed on the control grid in the vacuum tube, the vacuum tube will cease to conduct and in effect becomes an electronic circuit breaker. The device will work equally well whether the vacuum tube is in the plate circuit of the gas-filled tube or is in the cathode circuit of the gas-filled tube.

It is therefore an object of this invention to provide an improved means for breaking the circuit of a gas-filled tube which has once ionized by employing a vacuum tube in series with a gas-filled tube.

Other advantages, objects and uses of my invention will become apparent by referring to the drawings in which Figure 1 illustrates a circuit with the vacuum tube in the anode circuit of the gas-filled tube.

2

Figure 2 illustrates a similar circuit with the vacuum tube in the cathode circuit of a gas-filled tube.

For sake of illustration the drawings are described in connection with photoelectric inspection operation although my invention will apply equally well to any operation where the gas-filled tube is ionized by appropriate means and when it is desired to deionize the tube, a negative potential is placed on the control grid in the vacuum tube.

Referring to Figure 1, a gas-filled tube 10 is provided having an anode circuit 11, a cathode circuit 12 and a control grid 13. Vacuum tube 14 is connected in the anode circuit 11 in series with the gas-filled tube 10. The vacuum tube 14 has a cathode circuit 15, an anode circuit 16 and a control grid 17. The two tubes 10 and 14 are connected in series across a direct current source of potential in which the positive terminal of the direct current source is at 18 and is grounded at 19. In the particular illustration of Figure 1, the control grid 13 is controlled photoelectrically by the amount of light received by the phototube 19. The phototube 19 is connected in series with the resistor 20 across a source of direct current potential having its positive terminal at 21 and its negative terminal at 22. The control grid 13 is connected at 23 between the phototube 19 and the resistor 20. When the phototube 19 is in shadow, the control grid 13 is more negative than the cathode 12 and the gas-filled tube 10 will not conduct. However when the phototube 19 receives light, a positive potential is placed on the control grid 13 and if at the same time the positive potential is placed on the control grid 17, current will flow through the circuit employing the tubes 10 and 14. Once the tube 10 is ionized by such a condition, the control grid 13 will no longer be able to control the flow of current through the circuit although the tube 19 is placed in darkness, because this is a characteristic of a gas-filled tube as has been heretofore explained. However, the flow of current through the circuit from the point 18 to the point 19 can be stopped if the potential on the ground grid 17 is changed from positive to negative. In other words, the control grid 17 is effective at any time for stopping the flow of current through the circuit where as the control grid 13 can function only to initiate the flow but cannot stop the current once the tube 10 is ionized.

The particular manner of controlling the control grid is immaterial to my invention. The control grid could be connected to a switch which would alternate from a

positive potential to a negative potential. However in the illustration given, the control grid 17 is also controlled photoelectrically. This is done as follows:

A second vacuum tube 24 is provided having a control grid 25, an anode circuit 26, and a cathode circuit 27. The tube 24 is connected in series with a load resistor 28 and a biasing resistor 29 across a direct current source of potential having its positive terminal at 30 and its negative terminal at 31. The control grid 17 of the tube 14 is connected to the point 32 between the resistor 28 and the tube 24. By such a connection the tubes 14 and 24 are 180° out of phase. That is when tube 24 is conducting, tube 14 is rendered non-conducting and when tube 24 is non-conducting, tube 14 is conducting. The bias on the tube 25 is controlled by a photoelectric circuit employing the phototube 33 connected in series with a resistor 34 across a direct current source of potential having its positive terminal at 35 and its negative terminal at 36. The control grid 25 is connected between the phototube 33 and the resistor 34 at point 37. When the phototube 33 is in darkness a negative potential is placed on the control grid 25 so that the tube 24 will not conduct. If the tube 24 does not conduct, a positive potential is placed on the control grid 17 and the tube 14 is placed in condition for conducting a current. When the phototube 33 receives light, a positive potential is placed on the control grid 25 so that the tube 24 will conduct and because of the load resistor 28, the control grid 17 is driven negative and the tube 14 is placed in a condition so that it will not conduct a current.

In the anode circuit 11 is a relay coil 38 which actuates a relay switch 39. The relay switch is shown in the open position which is the condition when no current flows through tube 10. The relay switch may actuate a motor or any other suitable mechanism which is desired.

The operation of the device is as follows: When the tube 33 is in darkness, the tube 24 will not conduct and a positive potential is placed on the grid 17. This is the normal condition of the bias on the grid 17. For any operation regardless of the particular means for controlling the bias on the grid 17, the grid 17 is normally maintained positive and whether or not the current will flow through the circuit from the point 18 to the point 19 depends on the bias of the control grid 13. When the control grid 13 is driven positive by tube 19 receiving sufficient light, current will flow from point 18 to point 19 and will continue to flow until the control grid 17 is driven negative by the photocell 33 receiving light regardless of the condition of light on tube 19.

I want it distinctly understood that the particular means of controlling the grid 13 and the grid 17 is immaterial to my invention. It can be controlled in any manner depending upon the type of operation desired. My invention resides in a manner in which the gas-filled tube has its circuit broken once it ionizes. However, it is preferred to use two stage amplification for controlling the grid 17.

While the operation just described in many cases is satisfactory, it can be improved by connecting a circuit employing a choke coil 40 and a resistor 41 in parallel with the gas-filled tube 10. It has been found that there is a gradual tapering off of the amount of current that the tube 14 will conduct when a negative bias is placed on the control grid 17 and where it is desired to immediately stop the flow of current through the

tube 10 and avoid such tapering off as is desired in many operations, a choke coil should be employed as above described. A choke coil has the function of always conducting the current it is set for and in effect what the choke coil 40 does is to take all of the current from the positive terminal 18 and conduct it to ground when a negative potential is placed on the grid 17. This has the effect of immediately stopping the flow of current through tube 10 whereas otherwise there may be a small amount of current flow through tube 13 for a short time which is undesirable in some operations. The amount of current that a choke coil 40 will always conduct depends upon the point of adjustment of the adjustable resistor contact 42. The choke coil 40 itself has no control on the device but the minute the grid 17 is driven sufficiently negative that the choke coil will conduct all of the current from point 18 to point 19, the tube 10 will cease to conduct. The choke coil therefore has the effect of immediately stopping the flow of current through the tube 10 when the current through the tube 14 reaches a certain minimum. The choke coil has many advantages in operations where it is desired to immediately break the circuit so that tube 10 will not conduct.

The choke coil circuit embodying the choke coil 40 and the resistor 41 is connected in parallel with the tube 10 by connecting the circuit from point 43 to the ground 19.

Figure 2 is similar to Figure 1. The only real difference is that the tube 14 is in the cathode circuit of the tube 10 rather than in the anode circuit. The operation of the device in Figure 2 is substantially the same. The circuit employing the choke coil 40 and the resistor 41 is connected in parallel with the tube 10 by having it connected from the point 43 to the point 44. The vacuum tube 14 serves substantially the same function whether it is connected in the anode circuit of the tube 10 or connected in the cathode circuit of tube 10.

Throughout the specification and claims whenever I speak of a positive or negative potential, or a positive or negative bias, I mean the relative potential or bias of the control grid in respect with its cathode. The cathode and grid may both be at a positive potential but if the grid is more positive than the cathode, a positive bias or potential is placed on the grid. Likewise both may have a positive potential but if the grid is less positive than the cathode, a relatively negative potential is placed on the grid.

55 I claim as my invention:

1. An electronic circuit comprising a source of direct current, a first series circuit connected to said source comprising a vacuum amplifying tube and a gas-filled amplifying tube, each of said tubes having an anode circuit, a cathode circuit and a control grid, a second series circuit comprising a choke coil and a resistor connected in parallel with the gas-filled amplifying tube, the control grid of said vacuum tube being normally biased so as to enable the vacuum tube to conduct a current, independent voltage-applying means controlling the bias on the control grid of the gas-filled tube thereby controlling the ionization of the gas-filled tube and means for preventing or stopping the flow of current through the gas-filled tube including voltage-applying means for placing sufficient negative bias on the control grid of the vacuum tube to render the vacuum tube non-conducting.

75 2. An electronic circuit comprising a source of

direct current, a series circuit connected to said source comprising a vacuum amplifying tube and a gas-filled amplifying tube, a series circuit comprising a choke coil and a resistor connected in parallel with the gas-filled tube, each of said tubes having an anode circuit, a cathode circuit and a control grid, a third amplifying tube having a loaded anode circuit, a cathode circuit and a control grid, the control grid of said vacuum tube being connected to the loaded anode circuit of said third amplifying tube such that the two tubes are 180 degrees out of phase, the control grid of said third amplifying tube normally biased so as to enable the vacuum tube to conduct a current, independent voltage-applying means controlling the bias on the control grid of the gas-filled tube for controlling the ionization of the

gas-filled tube, and means for preventing or stopping the flow of current through the gas-filled tube including voltage-applying means placing sufficient positive bias on the control grid of the third amplifying tube which renders the vacuum tube non-conducting.
